UNITED STATES PATENT OFFICE.

FRANCIS BILLINGHAM, OF BROOKLYN, NEW YORK.

DESIGN FOR A LAMP OR LANTERN BODY.

SPECIFICATION forming part of Design No. 18,200, dated March 27, 1888.

Application filed February 3, 1888. Serial No. 262,938. Term of patent 14 years.

To all whom it may concern:

Be it known that I, FRANCIS BILLINGHAM, a citizen of the United States, and a resident of the city of Brooklyn, Kings county, and State 5 of New York, have invented and produced a new and original Design for the Body of a Lamp or Lantern, of which the following is a specification, reference being had to the accompanying drawings, forming part thereof, 10 in which—

Figure 1 shows a side elevation in perspective; Fig. 2, the form of horizontal sections on lines *a b* and *e f*; Fig. 3, the form of horizontal section on line *c d*.

15 The leading feature of my design consists in the curvilinear shape of outline or outer contour of the lamp-body proper—that is, exclusive of the form of the canopy, which may vary or be dispensed with.

20 A is a lamp-body proper, which, as is shown, is oval or egg-shaped in outer contour, with four flattened or plane surfaces, of oval or elliptical outline, depressing or breaking the curving lines of its four sides, so that horizontal

25 sections on the lines of *a b* and *e f* show circular outlines, and a horizontal section on the

line of *c d* will show the outline of a square with blunt corners, as shown by Figs. 2 and 3. Ornamental studs, as *i i i i*, are arranged on the curved surface of the body, substantially 30 as shown, thus breaking its plainness and producing a pleasing embellishment, which may be more conspicuous when of contrasting colors.

Having thus described my invention, I 35 claim—

The design for a lamp body herein shown and described, the same consisting of a curvilinear figure presenting an oval or egg-shaped form or outer contour with flattened sides, the 40 outlines of which are oval or elliptic, and having ornamental studs contrasting in color embellishing the curved surfaces, as shown and described.

In testimony that I claim the foregoing as my 45 invention I have signed my name, in presence of two witnesses, this 27th day of January, 1888.

FRANCIS BILLINGHAM.
